UNITED STATES PATENT OFFICE

CORNELIA B. FARADAY, OF NEW YORK, N. Y., ASSIGNOR TO BIGELOW SANFORD
CARPET CO., INC., A CORPORATION OF MASSACHUSETTS

DESIGN FOR A CARPET

Application filed March 12, 1931. Serial No. 39,038. Term of patent 7 years.

To all whom it may concern:

Be it known that I, CORNELIA B. FARADAY, a citizen of the United States, residing at New York city, in the borough of Manhattan and State of New York, have invented a new, original, and ornamental Design for a Carpet, of which the following is a specification, reference being had to the accompanying drawing forming part thereof.

The drawing illustrates a portion of a carpet showing my design.

I claim

The ornamental design for a carpet substantially as shown.

CORNELIA B. FARADAY.
